MACHINE FOR MAKING DOUBLE LOOP
HOOK AND TIE BANDSHenry G. Drake and James L. Wingate,
Gastonia, N. C.

Application May 4, 1944, Serial No. 534,072

2 Claims. (Cl. 57—26)

This invention relates to a method and machine for making double loop hook and single loop tie bands and it consists in the constructions, arrangements and combinations herein described and claimed.

It is the cardinal object of the invention to provide a single machine for making double loop and single loop tie bands, such as may be employed in connection with the driving of spindles of spinning frames, twisters, quillers, spoolers and card pulleys in textile mills.

It is a particular object of the invention to provide a machine of the kind specified, in which bands of definite lengths are produced, so as to be adaptable to use in the driving of spindles of a particular machine.

It is also an object of the invention to provide a machine of the character stated which is of extreme simplicity, of relatively few parts and readily operated by an average worker in textile mills.

Additional objects, advantages and features of invention will be apparent from the following description considered in conjunction with the accompanying drawings, wherein

Figure 1 is a top plan view of the machine.

Figure 2 is a side elevation thereof.

Figure 3 is a cross section on the line 3—3 of Figure 2.

Figure 4 is a cross section on the line 4—4 of Figure 2.

Figure 5 is a diagrammatic top plan view illustrating the first step in the twisting operation in the formation of a band.

Figure 6 is a similar view of a further step in the twisting operation.

Figure 7 is a view of the band after removal from the machine, and

Figure 8 is a view illustrating a partially completed band.

Figure 9 is a view illustrating the final twist of the band.

There is illustrated a twisting machine generally indicated by the reference character 10 consisting of a pair of upright standards 11—12, upon which there is suitably mounted a table or platform 13. Upon the underside of the table spaced inwardly of the standard 12 there is a bracket 14 extending downwardly in parallel relation to the standard 11. The standard 12 and the bracket 14 are each provided with aligned bearings for revolvably mounting a shaft 15. Upon the shaft 15 there is secured a pulley 16 and pulley 17, the former being driven from a motor 18 by means of a belt 19. Upon the table

13, above the standard 12 a pair of brackets 20 and 20' are mounted, extending vertically in parallel spaced relation, each of which is provided with three bearings arranged in triangular relation to each other, as may be seen in Figure 2. The bearings are in opposed aligned relation for mounting of respective shafts 21, 22, and 23, the shafts 21 and 23 being positioned at the same horizontal level and spaced laterally from the vertical axis of the brackets 20 and 20', while the shaft 22 is located in the vertical axis of the bracket, at a level approximately medially of the bracket. The shafts 21, 22, and 23 are the twisting spindles and project beyond the bracket 20', each shaft terminating in respective hooks 24, 25 and 26. The shaft 21 is of a length greater than the shaft 23, while the shaft 22 is of a length less than the shaft 23, as may be seen in Figure 1.

20 In order that the shafts may be rotated, the shaft 21 has a gear 27 keyed thereto in mesh with a gear 28 fixed to the shaft 22, this latter gear being in mesh with a gear 29, secured upon the shaft 23. The shaft 22 includes a fixed pulley 30 and a freely rotating pulley 31 arranged in close parallel relation and aligned with the drive pulley 17. A belt 32 is normally trained about the pulley 17 and pulley 30, and may be shifted laterally so as to engage the free pulley 31 by actuation of the belt shifter 33 suitably mounted upon the underside of the table 13. The table is slotted as at 34, to permit passage of the belt to the pulleys 30 and 31.

25 As may be seen in Figure 3, the shaft 22 rotates in a clockwise direction while the shafts 21 and 23 rotate in a counter-clockwise direction.

30 The table 13 supports a trackway 35 extending longitudinally thereof, and as shown in Figure 4, 35 consists of a pair of spaced parallel rail members 36 upon the upper edges of which there is secured respective strips 37, of a width greater than the rails so as to overhang the inner faces of the latter. A tension block 38 is slidable between the guide rails 36 held therewithin by the strips 37. Upon the block 38 there is a bracket 39 provided with a bearing 40, of any suitable anti-friction type, through which a hooked spindle 41 is journaled. The hook 42 of the spindle 45 is directed in the direction of the spindles 21—22 and 23.

35 There is illustrated a trackway 35 extending longitudinally thereof, and as shown in Figure 4, 40 consists of a pair of spaced parallel rail members 36 upon the upper edges of which there is secured respective strips 37, of a width greater than the rails so as to overhang the inner faces of the latter. A tension block 38 is slidable between the guide rails 36 held therewithin by the strips 37. Upon the block 38 there is a bracket 39 provided with a bearing 40, of any suitable anti-friction type, through which a hooked spindle 41 is journaled. The hook 42 of the spindle 45 is directed in the direction of the spindles 21—22 and 23.

45 An adjustable stop 43 is employed consisting of a narrow block of a length to fit between the rails 36. The stop 43 includes studs 44 adapted to fit within suitably spaced apertures 45 formed

50 in the trackway 35. The stop 43 is suitably secured to the block 38.

in the table 13. The stop 43 occupies a position rearwardly of the block 38 and when making an adjustment for a desired length of band, the block 38 is slid forwardly and the stop is then moved so that the studs 44 register with the desired apertures 45, the latter being spaced longitudinally so as to determine the length of the band.

A slideable pegging block 46, commonly known as the leader, is positioned in advance of the tension block 38 in abutting relation, the blocks 38 and 46 being held yieldingly against the stop 43, and in the present instance, this is accomplished by means of a strand 47 anchored to the pegging block, passed rearwardly over a pulley 48 suitably mounted at the adjacent end of the table; a weight 49 being secured to the free end of the strand. Another strand 47' is anchored to the block 38 and also passed rearward over a pulley similar to the one 48. A weight is also secured to the free end of this strand.

The operation of the machine and production of a band will be now described:

Size of the band is determined by the number of strands and the size of the yarn used (which may number from 2's to 60's) and also the number of revolutions wound about the twisting spindles. Ordinarily, twelve or fourteen strands of 8's or 10's single twist knitting yarns are attached to the hook 24 of spindle 21 and carried to the rear end of the machine where it is passed around hook 42 of spindle 41, thence to the front of the machine where the thread is passed around the hook 26 of spindle 23. Procedure is then reversed and yarn is carried back around the hook 42 of the spindle 41, thence forwardly to hook 24 on spindle 21. This manipulation of the thread is indicated by arrows in Figure 5. This completes one revolution.

On larger bands, revolutions are made according to size of band to be produced, and size of yarn used.

After two revolutions are completed, strands of threads are passed between yarn on spindle 21, thence around hook 24, and out, leaving five or six inches of free end with which to splice together ends looped around the spindles 21 and 23, after twisting motion has been completed.

Spindle 50 now is inserted in the hole in block 46, being placed between yarn mounted on spindles 21 and 23. The function of this spindle is to separate and prevent yarn from twisting together on first twist and to even the second twist.

Since the belt 32 would be engaged with the free pulley 31 the belt is shifted by lever 33 onto fixed pulley 30, thus imparting rotating motion to spindles 21 and 23 through gears 27, 28 and 29. A twisting motion is thus imparted to the thread and blocks 38 and 46 will commence to move forward on the trackway 35, due to contraction of the twisted thread.

As twisting motion continues, rotating tension on the strands becomes great enough to cause spindle 41 to rotate automatically, twisting the two separate strands together, thus creating the second twist (see Fig 6). As the second twist continues, the spindle 50 will chase the two strands being twisted together toward the twisting spindles 21 and 23. At this point, belt 32 is shifted back on the loose pulley and rotation of the spindles is stopped. Spindle 50 is now removed from between the twisted strands. (At this point of manufacture, if the operator so desires he may cut or otherwise sever ends

mounted on spindles 21 and 23. Tie bands may be produced by the operation up to this point.)

The loose long end of strands mounted on spindle 21 is now threaded through a bailing needle 51 (see Fig. 7), and in turn is sewed through loops formed on spindles 21 and 23, the loop is then removed from the spindle 23, and drawn up tight to and sewed through the loop formed on the spindle 21. Needle 51 is now passed through two sections of the strand forming a knot joining the two sections together. However, this leaves a small space 52 (see Fig. 8), that does not have sufficient second twist, or what might be termed a loose or soft end.

15 In order to eliminate this loose or soft end, the second twist must be equalized, on the loose end. This is accomplished by reversing ends, by mounting the end originally mounted on spindles 21 and 23, now joined together, on the hook of 20 the spindle 41. The opposite end (originally mounted on hook of spindle 41), is now connected to hook 24 of spindle 21. A cone-shaped spindle 50' known as a peg, is inserted between the strands connected to the spindle 41 (see Fig. 9). The machine is started again and spindle 21 (thread being held by peg 50' at the other end) removes some of the twist adjacent the spindle 21 and at the same time puts in twist on end near spindle 41. As twist on loose end is being 30 put in peg 50' is chased up second twist toward spindle 21. The end that was mounted on spindle 21 is removed and is now connected onto the hook 25 of spindle 22. Spindle 41 is held stationary by the right hand and belt 32 is shifted 35 to fixed pulley, then immediately shifted back to loose pulley. Spindle 41 is released, the band removed from the spindles, and is complete with a loop at each end.

Twister bands, spinning bands, spooler bands or card bands are made by identically the same procedure, except that the number of revolutions the strands wound around spindles 21, 41 and 23 are increased or decreased according to 45 the size in diameter of the bands, or according to the size of yarn used.

The bands made on this machine are superior to the old type known as tie bands in that they will last considerably longer under same circumstances, and will make yarn of an evener twist due to the fact that the bands are made the same length and exert the same tension between the driving cylinders and the whirls, on the spinning, twisting or spooler machines.

While we have disclosed the invention in detail in the best form known to us, it will, nevertheless, be understood that this is purely exemplary, and that various modifications in the construction, arrangement and combination of parts may be made therein without departing from the spirit of the invention, except as more specifically limited in the appended claims, wherein:

We claim:

1. A machine for forming a double loop band comprising an elongated table, a longitudinally extended trackway on said table, said trackway having a series of longitudinally spaced apertures, spaced frame members on one end of said table, a pair of shafts journaled in upper portions of the frame members, a third shaft journaled in the frame members at a point medially thereof, each of the shafts lying in a plane parallel to the top of the table and terminating in respective hook members, means for starting and stopping rotation of the shafts, a stop member longitudinally adjustable within the trackway

including studs complementary to the apertures of the trackway, a tension block slidably mounted within the trackway, said tension block having a freely rotatable shaft positioned parallel to the top of the table, and terminating in a hook member disposed in opposed relation to the first named hook members and adapted to receive strand members operatively connected with hooks of the first named pair of shafts, said freely rotatable shaft being in alignment with the third named shaft, for mounting of a partially completed band therebetween, a leader block in advance of the tension block, a removable vertically disposed pin in said block in advance of the freely rotatable shaft and associated hook member and yielding means for holding said blocks against said stop.

2. A machine for forming a double loop comprising an elongated table, a longitudinally extended trackway on said table, vertically disposed parallel frame members on one end of the table, a pair of shafts journaled in upper portions of the frame members, a third shaft journaled in the frame members at a point medially thereof, each of the shafts lying in a plane parallel to the top of the table and terminating in respective hook members, a gear fixed to the third named shaft in mesh with respective gears

fixed to the upper pair of shafts, a fixed pulley and a loose pulley on the third shaft, a driven shaft revolvably mounted beneath the top of the table, said shaft having a pulley mounted thereon, said pulley being aligned with said fixed and loose pulleys, a belt trained about said fixed pulley and the pulley on said driven shaft, shifter means for moving said belt to said loose pulley, means for driving the driven shaft, a stop member longitudinally adjustable within the trackway, a tension block slidably mounted within the trackway, said tension block having a freely rotatable shaft positioned parallel to the top of the table and terminating in a hook member disposed in opposed relation to the first named hook members and adapted to receive strand members operatively connected with hooks of the first named pair of shafts, said freely rotatable shaft being in alignment with the third named shaft for mounting of a partially completed band therebetween, a leader block in advance of the tension block, a removable vertically disposed pin in said block in advance of the freely rotatable shaft and associated hook member and yielding means for holding said blocks against said stop.

HENRY G. DRAKE.
